[57] ABSTRACT

A fibrous ceramic insulating blanket is wrapped around the water-cooled pipes in a steel processing reheating furnace. The resilient blanket, in sections, is pressed onto threaded anchor studs projecting from the pipes and is held in place by ceramic anchors placed over each stud and secured to the stud by a lock nut. A ceramic mortar covers the lock nut seated in a depression in the ceramic anchor. The assembly is then sprayed overall with a liquid rigidizer which upon hardening provides a relatively hard and erosion resistant outer layer over a resilient inner layer.

FIG. 8

INSULATION FOR WATER-COOLED PIPES IN A REHEATING FURNACE

This invention relates to skid rail systems in steel processing reheat furnaces and more particularly to the insulation of the skid rail system members from the high temperatures of the reheating process.

In the processing of steel, ingots are rolled into shapes such as blooms or slabs and subsequently heated again in reheating furnaces for further rolling. In conventional reheating furnaces the slabs or blooms to be reheated are pushed through the furnace on horizontal skid rails held in spaced relationship by transverse members. This structure is in turn supported by vertical supports in such a manner that heating may take place on both the top and bottom of the slab or bloom. The supporting member for the skids, the transverse members and the vertical supports are water-cooled pipes. These pipes must be insulated to prevent absorption of too much of the heat supplied to the furnace.

Typically, this insulation is a rigid-preformed or cast refractory material placed around the skid support pipe, the vertical supports and the transverse members as shown, for example, in Corriston, U.S. Pat. No. 2,022,649 or Greaney, U.S. Pat. No. 3,329,414 or the preformed refractory material may be combined with resilient layers as shown in Barker, U.S. Pat. No. 3,451,661. However, pushing slabs or blooms along the skids during the heating process, causes the skids to flex and also creates vibrational shocks between the slabs and skids. The effect of the shocks and the flexing is the premature breaking away of the rigid preformed or cast refractories thereby exposing the pipes to destructive high heat. This results in excessive fuel consumption and additional costs to replace insulation before the normal expected life of the refractory.

In accordance with our invention a fibrous ceramic insulating blanket is wrapped completely around the supporting and transverse pipes and partially around the skid rail support pipes and pressed into a series of threaded alloy studs projecting outwardly from the pipes. A refractory anchor is inserted over each stud and held in place by a lock nut which is covered by a layer of high temperature mortar. The entire assembly is then sprayed with a rigidizer providing an insulation resistant to destruction from vibration and chatter, eliminating the problems of high fuel consumption and repair costs.

It is therefore an object of our invention to provide an insulation for water-cooled pipes in a reheating furnace that is resistant to damage or destruction caused by vibrations.

Another object is to provide such insulation that is simple to install and reduces fuel and maintenance costs.

These and other objects will become more apparent after referring to the following specification and drawings, in which:

FIG. 1 is a fragmentary perspective view of a reheating furnace showing the conventional arrangement of skid rails, transverse members and supporting members;

FIG. 2 is a plan view of part of the structure showing the insulation;

FIG. 3 is an enlarged elevation of a portion of a vertical support member;

FIG. 4 is a sectional view taken along line III—III of FIG. 3;

FIG. 5 is an enlarged elevation of a portion of a transverse member;

FIG. 6 is a sectional view taken along line V—V of FIG. 5;

FIG. 7 is an enlarged elevation of a portion of a skid member; and

FIG. 8 is a sectional view taken along line VII—VII of FIG. 7.

Referring now to FIG. 1, reference numeral 2 indicates the wall and reference numeral 4, the floor of a reheat furnace. Projecting upwardly from floor 4 is a series of vertical supports 6, supporting transverse members 8. Slabs S move on a series of parallel skid rails 10 supported on pipes 12 which are in turn supported on transverse members 8. This is a conventional reheating furnace.

Referring now to FIGS. 3 and 4, vertical support member 6 includes a steel pipe 14 which may be about 3 inches in diameter with about $\frac{1}{8}$ to $\frac{3}{4}$ inch wall thickness. Threaded $\frac{1}{4}$ -inch alloy steel anchor studs 16, about 1- $\frac{1}{4}$ inch long are welded to pipe 14 in pairs, projecting opposite each other from the circumference of the pipe, at about 1 foot intervals along the pipe. A 1 $\frac{1}{2}$ inch thick alumina silica fibrous refractory blanket 18, such as "Fiberfrax H" manufactured by The Carborundum Company, is wrapped completely around pipe 14 in two foot lengths with the section ends butted together. Although FIG. 3 shows a joint 20 between two sections of blanket at the same location as a pair of studs 16, joint 20 may be located without regard to stud locations. It is preferred, however, to locate a joint 22, also a butt joint, between the two ends of a single section of blanket at a stud 16. A refractory anchor 24, about 2 inches in diameter and about 1 $\frac{1}{8}$ inch long with a hole 26 to accommodate the stud is placed on each stud 16. An alloy steel lock nut 28 secures the anchor to the stud, the nut fits into a protective recess 30 in the outer end of anchor 24. Anchor 24 may be made of a high alumina castable refractory, a high duty fire brick. Blanket 18 is compressible, and when lock nut 28 is fully seated, a slight dimple 32 is made in blanket 18. After nut 28 is secured, it is covered by a quantity of a ceramic mortar 34 sufficient to protect nut 28 from the heat. Mortar 34 may be a Multiplex High Alumina Castable Refractory manufactured by the Chicago Fire Brick Company. The entire installation is then sprayed with a rigidizer, a water soluble silicate such as an alkali silicate of the type known as Fiberfrax Rigidizer manufactured by The Carborundum Company, for the blanket insulation 18. The rigidizer is a liquid binder which, upon drying, increases the hardness and erosion resistance of the blanket. The rigidizer contains silica and penetrates about half way 36 through blanket 18.

Referring now to FIGS. 5 and 6, pipe 38 of transverse member 8 may be about 5 inches in diameter with about $\frac{1}{8}$ - to $\frac{3}{4}$ -inch wall thickness. Blanket 18 is attached in the same manner as on vertical supports 6. Joint 22 is conveniently placed on the bottom of pipe 38 and a bottom row of studs 16 on pipe 38 preferably has a stud located at each joint between each two foot long blanket section and an additional stud spaced between the studs located at the joints. An additional row of studs is placed on each side of pipe 38 spaced to provide two studs on each side for each two foot long section of blanket 18.

FIGS. 7 and 8 show a similar insulation procedure for the insulation surrounding pipe 12 which supports skid

5 rail 10. Pipe 12 may be about 4 inches in diameter and about $\frac{5}{8}$ - to $\frac{3}{4}$ -inch thick. A row of studs 16 is placed on each side of pipe 12 with an anchor on each side at each joint 20 (FIG. 2) between sections of blankets 18, and an additional stud in each row spaced between the studs located at the joints. Blanket 18 is not wrapped entirely around pipe 12, but is spaced away from skid rail 10 a sufficient distance so that a slab moving along rail 10 will not contact the ends 40 of blanket 18.

10 The rigidizer is preferably applied after all the insulation blanket 18 has been applied to all the pipes 12, 14 and 38. The insulation installed as described provides a long lasting insulation resulting in lower material and replacement labor costs and fuel consumption than the rigid type insulation because there is sufficient resiliency to resist destructive vibration caused by movement of slabs along the skid rails.

15 We claim:

1. Vibration resistant insulation for water cooled members of a skid rail system in a reheating furnace comprising

20 a plurality of permeable resilient fibrous alumina-silica blanket sections wrapped around the water cooled members in abutting relationship,

25 means attached to said members for holding said blanket sections in place around said members; and

30 a ceramic rigidizer applied to the outside of said blanket sections while held in place around said members and penetrating partially into the blanket sections thereby providing a rigidized outer layer and

5

a resilient inner layer.

2. Insulation according to claim 1 in which the rigidizer is applied to effect about half the thickness of the blanket sections.

3. Insulation according to claim 1 in which the means for holding said blanket sections in place around said water cooled members includes

10 a plurality of threaded studs attached to the members and projecting outwardly through the blanket sections,

a refractory anchor adapted to fit over each stud for holding the blanket sections in place while slightly compressing the blanket section adjacent the anchor,

15 a lock nut for holding each anchor onto a stud,

a recess in each anchor for receiving the lock nut below the outer surface of the anchor with the end of the stud being below the outer surface of the anchor when the anchor is in position, and

20 ceramic mortar filling each recess thereby covering the lock nut and stud end.

4. Insulation according to claim 3 in which the rigidizer is applied to effect about half the thickness of the blanket sections.

5. Insulation according to claim 4 in which the refractory anchor and ceramic mortar are each a high alumina castable refractory.

30 6. Insulation according to claim 5 which includes one of said studs at each blanket section joint.
